MOISTENING DEVICE FOR DUPLICATING MACHINES

Filed Oct. 24, 1945

FIG. I.

FIG. 2.

INVENTOR:
Frank Ronald Ford.
By Richardson and David
ATTY's

UNITED STATES PATENT OFFICE

2,505,035.

MOISTENING DEVICE FOR DUPLICATING MACHINES

Frank Ronald Ford, Sparkbrook, Birmingham, England

Application October 24, 1945, Serial No. 624,262
In Great Britain August 25, 1945

2 Claims. (Cl. 101—132.5)

1

This invention relates to duplicating machines of the class in which a copy sheet and a master sheet bearing in reversed script the matter to be reproduced are passed in pressure contact between a cylinder which carries the master sheet and a pressure roller, the copy sheet being moistened by a suitable device before being brought into contact with the master sheet.

The invention has particular reference to machines of the type described in the specification of my prior application Serial No. 540,486, filed June 15, 1944, which has matured into Patent No. 2,491,368, December 13, 1949. In such machines, the moistening device comprises an absorbent pad across which the copy sheets are drawn and which is adapted to be fed with liquid from a tank by means of a feed wick supported on an operating member, this latter being spring-biassed in a direction towards the pad and capable of being displaced in the reverse direction (so as to interrupt the feed of liquid to the pad) by angular movement of a rock-shaft.

Machines of the class to which the present invention relates are usually provided with means whereby, after each copy has been made, the rotation of the cylinder is checked by an automatic device and a damping bar employed to press the copy sheets against the moistening pad is moved away from the latter at this stage to enable a fresh copy sheet to be fed, between the damping bar and the pad, to the nip between the cylinder and the pressure roller.

In my prior specification aforesaid, I have described mechanism whereby, at the end of each operative cycle of the machine (i. e. on separation of the damping bar from the pad), the rock-shaft is automatically turned so as to interrupt the liquid feed to the pad in the manner above described, over-riding means being also provided whereby a person using the machine is enabled to cut off the liquid feed, independently of the automatic operation, whenever such action may seem to be desirable.

The object of the present invention is to provide improved control means for the liquid feed which will also enable the feed wick or wicks to be left permanently in contact with the moistening pad, when desired, regardless of whether the cylinder is rotating or not.

According to this invention, the control means comprises a member adapted in one position to permit automatic oscillation of the rock-shaft to alternately interrupt and re-establish the liquid feed during operation of the machine, such control member, in an alternative position, retaining

2

the rock-shaft in the "feed interrupted" condition and, when moved to a second alternative position, disabling the rock-shaft actuating mechanism so that liquid is fed continuously to the moistening pad.

In the drawings:

Figure 1 is a view in side elevation showing part of a duplicating machine having the improved liquid feed control means; and

Figure 2 is a sectional view in side elevation showing the liquid feed means.

Figure 2 is drawn to a larger scale than Figure 1.

As illustrated, the machine comprises spaced side members 1 secured together by suitable tie-rods and having mounted between them a transversely disposed impression cylinder 2 and a moistening device 3 similar to that described in the specification of my prior application Serial No. 540,486.

In such a device the supply of liquid from the liquid 25 in the reservoir 3 to a wick 23 supporting the moistening pad 26 over which the copy sheets 19 pass is effected by means of at least one feed wick 20 the upper end of which is attached to a bar 21 slidable on a support 27, which bar is spring-biassed by a plate spring 24 in the direction of the wick 23, the bar 21 being slidable in the reverse direction by suitable angular movement of a rock-shaft 4 having crank arms 22 which engage the bar 21. In the arrangement shown, separation of the feed wick or wicks 20 from the wick 23 is effected by anti-clockwise movement of the rock-shaft 4.

Fixedly or otherwise attached to one end of the shaft 4 is an arm 5 of square or other non-circular section on which is slidably mounted an abutment 6. This latter may have a tubular portion 7 which is guided on the arm 5 and which is normally held against a stop 8 by means of a tension or other spring 9.

In this normal position of the abutment 6, the latter is disposed immediately above the axis of the cylinder 2, at the end of which is mounted a disc 10 carrying a crank-pin 11. Obviously the crank-pin may be replaced by a cam designed to give a similar lift, if desired. As the cylinder 2 rotates in the direction of the arrow, this crank-pin 11 periodically engages an inclined face 12 on the abutment 6 and effects, one in each revolution of the cylinder, an anti-clockwise movement of the arm 5 and shaft 4 sufficient to effect interruption of the liquid feed. Return movement of the arm 5 is, of course, effected by the

biassing spring associated with the bar carrying the feed wick or wicks.

Pivotsly mounted at 13 below the arm 5 and movable in the same or a parallel plane is a two-armed rocking lever 14 which is manually operable by means of a handle 15 on one arm thereof.

This lever 14 may be moved to any of three angular positions indicated by markings on the side member 1 or some other convenient part 10 of the machine.

These markings, which may be on a curved scale 16 adjacent the handle 15, conveniently comprise the words "Auto" (or "Automatic"), "Off," and "On."

When it is desired to provide for automatic interruption of the liquid feed at the end of each operation cycle of the machine, the handle 15 is moved to the appropriate mark on the scale 16, and in this position the handle-carrying arm of the lever 14 is disposed substantially horizontally. The second arm 17 of the lever (which may be substantially shorter than that carrying the handle) lies, under these conditions, in the position indicated in dotted lines to the right of the pivot 13 so that it does not affect movement of the arm 5.

If it should be thought desirable to maintain the feed wick or wicks separated from the moistening pad, the handle 15 is moved to the "Off" position indicated in full lines in the drawing, whereupon the arm 17 of the lever 14 engages the underside of the sleeve 7 and rocks the shaft 4 into, or retains it in, a position corresponding to that into which it is lifted by the crank-pin 11 during the automatic operation above described.

Should the moistening pad have become unduly dry (for example, when the machine is to be restarted after standing idle for a lengthy period), the lever 14 is given a further movement in the same direction until the handle 15 is opposite the "On" marking on the scale 16.

The short arm 17 of the lever is thus moved in the position indicated in dotted lines to the left of the pivot 13, and during such movement the arm engages a downwardly projecting lug 18 on the sleeve 7 so that the latter, together with the abutment 6, is slides along the arm 5 against the action of the spring 9.

In the "On" position of the lever 14, the abutment 6 is held clear of the orbit of the crank-pin 11, so that the arm 5 and shaft 4 are permitted to turn clockwise until the feed wick or wicks make contact with the pad and remain in this position regardless of whether the cylinder 2 is rotated or not.

What I claim then is:

1. In a duplicating machine, the combination of a rigid frame, an impression cylinder rotatably mounted in said frame, a copy sheet moistening device containing liquid, a rock-shaft associated with said moistening device, the rate of liquid feed to the copy sheets being controlled by the angular position of said rock-shaft, an actuating arm carried by said rock-shaft, a cam or the equivalent rotating with said cylinder, said actuating arm extending across the end of the cylinder above said cam or equivalent, an abutment having a tubular part slidable on said arm 70

and having an inclined face adapted to be engaged by said cam or equivalent, a stop on said arm defining the normal position of said abutment, spring means biassing said abutment towards said stop, a lug on said tubular part and projecting downwardly therefrom, a two armed rocking lever pivoted to the frame on an axis parallel to that of the cylinder, said rocking lever forming a control lever, one arm of the rocking lever being adapted to be moved into any one of three positions, in one of which it is approximately at right angles to said arm and supports it in a raised position with the inclined face clear of the path of movement of the cam or its equivalent, in another of which it supports the arm in a lower position with the inclined face in the path of movement of the cam or its equivalent, and in the third of which it engages the said lug and slides the abutment along said arm and brings the inclined face out of the path of movement of the cam or its equivalent while supporting the arm in a lowered position, and means for moving said control lever into each of the said three positions.

2. In a duplicating machine, the combination of a rigid frame, an impression cylinder rotatably mounted in said frame, a copy sheet moistening device containing liquid, a rock-shaft associated with said moistening device, the rate of liquid feed to the copy sheets being controlled by the angular position of said rock-shaft, an actuating arm carried by said rock-shaft, a cam or the equivalent rotating with said cylinder, said actuating arm extending across the end of the cylinder above said cam or equivalent, an abutment having a tubular part slidable on said arm and having an inclined face adapted to be engaged by said cam or equivalent, a lug on said tubular part and projecting downwardly therefrom, a two armed rocking lever pivoted to the frame on an axis parallel to that of the cylinder, said rocking lever forming a control lever, one arm of the rocking lever being adapted to be moved into any one of three positions, in one of which it is approximately at right angles to said arm and supports it in a raised position with the inclined face clear of the path of movement of the cam or its equivalent, in another of which it supports the arm in a lower position with the inclined face in the path of movement of the cam or its equivalent, and in the third of which it engages the said lug and slides the abutment along said arm and brings the inclined face out of the path of movement of the cam or its equivalent while supporting the arm in a lowered position, and a handle operatively connected to said control lever for moving the same into and out of its alternative locations, and markings provided externally of said frame to indicate the various handle positions.
